(No Model.)

T. BOLTON.

INSOLE FOR BOOTS OR SHOES.

No. 298,278.

Patented May 6, 1884.

Attest,
John F. Osgood
T. Bolton

Inventor:
Thos. Bolton,
John F. Osgood,
Atty.

UNITED STATES PATENT OFFICE.

THOMAS BOLTON, OF ROCHESTER, NEW YORK.

INSOLE FOR BOOTS OR SHOES.

SPECIFICATION forming part of Letters Patent No. 298,278, dated May 6, 1884.

Application filed February 15, 1884. (No model.)

To all whom it may concern:

Be it known that I, THOMAS BOLTON, of the city of Rochester, county of Monroe, and State of New York, have invented a certain new and 5 useful Improvement in Insoles for Boots or Shoes; and I do hereby declare that the following is a full, clear, and exact description of the same, reference being had to the accompanying drawings, in which—

10 Figure 1 is a plan view of the insole. Fig. 2 is a cross-section of the same.

My improvement relates to insoles for boots or shoes, designed to promote flexibility and ease in wear; and it consists of an insole having its face cut with numerous incisions part way through, said incisions extending transversely and crossing each other diagonally, so as to leave diamond-shaped spaces between the cuts, as hereinafter more fully described 20 and definitely claimed.

In the drawings, A shows the insole, which is of usual form. *a a* and *a' a'* are the incisions or slits made in one face of the sole and on the foot portion only. These incisions are made 25 by a sharp instrument or tool forming a thin cut, and extend but part way through the sole, leaving the opposite face of the sole uncut. They are formed in two series extending diagonally across the sole and crossing 30 each other, as shown, and leaving diamond-shaped spaces between. It is designed to make the cuts quite near together and with a thin-edged instrument, so that the cuts will close together and leave a smooth surface.

35 Thus prepared the cut surface is scarified by close and fine lines over its whole extent.

I am aware that insoles are in use in which

slits are cut transversely and straight across the insole at regular intervals apart, said slits extending through the insole, the object being 40 to increase the flexibility. Such flexibility is secured by a corresponding weakening of the insole, as it is cut into narrow strips nearly across, which leaves the center portion unsupported and without proper strength, the 45 stitching holding only in a narrow margin. My invention consists not simply in cutting cross-slits, but in so scarifying the surface by diagonal cross-cuts located near together and extending but part way through that the upper 50 surface is made of uniform flexibility and softness over its whole extent, while the under surface is left uncut and retains all its strength.

This invention is particularly applicable to 55 shoes made on the McKay sewing-machine.

Having described my invention, I disclaim an insole having cross-slits extending through the insole; but

I claim—

As an improved article of manufacture, an insole having one face provided with two series of cross incisions or slits crossing each other in a diagonal direction, extending but part way through, and producing a scarified 65 surface, the opposite face of the insole being uncut, as herein shown and described.

In witness whereof I have hereunto signed my hand in the presence of two subscribing witnesses.

THOS. BOLTON.

Witnesses:

P. A. COSTICH,
R. F. OSGOOD.
